UNITED STATES PATENT OFFICE.

JAMES MACPHAIL, OF WEST PULLMAN, ILLINOIS, ASSIGNOR TO THE PLANO MANUFACTURING COMPANY, OF CHICAGO, ILLINOIS.

OIL-CUP.

SPECIFICATION forming part of Letters Patent No. 609,204, dated August 16, 1898.

Application filed October 1, 1897. Serial No. 653,766. (No model.)

To all whom it may concern:

Be it known that I, JAMES MACPHAIL, a citizen of the United States, residing at West Pullman, in the county of Cook and State of Illinois, have invented a certain new and useful Improvement in Oil-Cups, which is fully set forth in the following specification, reference being had to the accompanying drawings, in which—

10 Figure 1 is a plan view of my improved oil-cup. Fig. 2 is a section of the same on the line 2 2 of Fig. 1. Fig. 3 is a similar section with the cover elevated to permit of the insertion of the oil. Fig. 4 is a plan view similar to Fig. 1, but with the cover and the spring removed. Fig. 5 is a front elevation of the cover. Fig. 6 is a side elevation of the cover, and Fig. 7 is a rear elevation of the cover.

15 My invention relates to an improved and useful oil-cup for bearings and is intended to produce an oil-cup that can be cheaply manufactured and that will be durable in its construction, effective in operation, and incapable of getting out of order.

20 My improved oil-cup is intended, primarily, for use on farming implements; but it will be understood that it can be used wherever bearings are to be oiled.

25 In the drawings, A represents a portion of a cylindrical casting forming a portion of the bearing for a shaft, and B is the oil-cup proper, which may be cast with the part A. On its outside the cup B may be of a cylindrical shape, and its interior surface may 30 have the same general shape. An aperture D leads from the oil-cup to the bearing for the purpose of permitting the oil in the cup to reach the bearing.

35 In order to protect the cup from dirt, I provide a cap or cover G, which consists of a flat plate having the outline shown in Fig. 1 and having the wing K projecting therefrom at substantially right angles thereto. This wing K projects into the interior of the cup B and 40 has a concave bearing-surface H, which engages with the convex bearing-surface E, which forms one edge of the aperture C, forming the top of the cup. Projecting forwardly from the wing K is a lug L, which is opposed 45 in position to a lug F, which projects rearwardly and downwardly from the upper por-

tion of the inner front wall of the cup B. A helical spring M is interposed between said lugs F and L, and it will be seen from an inspection of Figs. 2 and 3 that the action of 55 this spring M, coöperating with the lugs F and L, is to hold the cover G firmly down upon the top of the cup B and prevent any dust or dirt from entering said cup. When one edge of the cover is lifted to the position 60 shown in Fig. 3, the spring M is put under increased tension and immediately returns the cover G to its normal position as soon as it is released. A pair of ribs J are located on the under side of the plate or cover G and 65 serve to strengthen said cover and to assist in holding the cover in its correct position, as when the cover is down. The ends of the ribs J are substantially against the front edge and sides of the aperture C. For convenience in raising the cover I form a portion 70 N of the cover G, which overlaps the cup B, as clearly shown in Fig. 2, and forms a projection to be grasped in raising said cover. The two principal parts of this oil-cup are 75 cast, and they, with the spring M, constructed and combined as shown, furnish a dust-proof cup that can be cheaply constructed and cannot readily get out of order.

Having described my invention, what I 80 claim as new, and desire to cover by Letters Patent, is—

1. An oil-cup consisting of the cup proper having an aperture, and a pivotal bearing-surface on the inner edge of said aperture, 85 with the cover having a pivotal bearing-surface coöperating with said other bearing-surface and adapted, when closed, to rest upon the top of the cup, and a spring interposed between said cup and said cover to hold it 90 normally closed, substantially as described.

2. An oil-cup comprising the cup B having the pivotal bearing-surface E and the lug F, with the cover having the bearing-surface H and the lug L, and the spring M interposed 95 between said lugs.

3. An oil-cup comprising the cup proper having the pivotal bearing-surface and the lug F, with the cover having the lug L, and the overlapping portion N, and the spring 100 interposed between said lugs, substantially as described.

4. The oil-cup comprising the cup B having the aperture C, the bearing-surface E, and the lug F, with the cover G having the bearing-surface H, the ribs J, and the lug L, and the spring M, all coöperating, substantially as and for the purposes described.

5. In an oil-cup for bearings, the cup proper cast integral with the bearing, and having an aperture and a pivotal bearing-surface on the inner edge of said aperture, with the cover having a pivotal bearing-surface coöperating with said other bearing-surface and adapted, when closed, to rest upon the top of the cup, and a spring interposed between said cup and said cover to hold the bearing-surfaces in contact and the cover closed, substantially as described.

6. An oil-cup comprising the cup proper having an aperture, said aperture having a pivotal bearing-surface on one edge thereof,

with the cover for said aperture having a pivotal bearing-surface on one side thereof coöperating with said other bearing-surface, an arm projecting into said cup, and a spring in said cup interposed between said arm and cup to hold the bearing-surfaces in contact and the cover closed, substantially as described.

7. An oil-cup for bearings comprising a cup proper having an aperture, a cover pivoted at the inner edge of such aperture and having an arm projecting into the cup and a spring abutting at one end against the arm and the other end against the cup at a point substantially opposite the edge of the aperture upon which the cover is pivoted.

JAMES MACPHAIL.
